CLAIM

The ornamental design for the guitar strap utilizing alternating long and short hardwood strips, as shown and described.

DESCRIPTION

FIG. 1 is a top perspective view of a guitar strap utilizing alternating long and short hardwood strips showing my new design, the strap is shown broken away to indicate an indeterminate length;

FIG. 2 is a fragmentary perspective view revealing length adjustment detail at one end of the strap;

FIG. 3 is a fragmentary enlarged top view revealing the spacing of the hardwood strips at the right hand end of the guitar strap shown in FIG. 1 with a buttonhole tab removed; FIG. 4 is a fragmentary enlarged bottom view of the edge of the guitar strap;

The broken lines shown at the extreme right on the button-hole tab of the guitar strap in FIG. 1 represent conventional stitching.
